Application January 7, 1955, Serial No. 480,504

6 Claims. (Cl. 200—93)

The present invention relates to circuit making and breaking apparatus and more particularly to a novel form of contactor assembly which will be found useful in connection with electrical circuits associated with a large variety of equipment, particularly electrical equipment involving a reversible motor circuit or a plurality of individual circuits.

The invention has been illustrated herein in the form of an electromagnetically operated contactor assembly having dual pairs of contacts capable of being alternatively opened and closed to alternatively establish or energize a pair of work circuits each containing a suitable load, as for example the field windings of a reversible motor. The invention is however susceptible to modification and, if desired, the contactor may be designed for single or plural working circuit operations.

It is among the principal objects of the present invention to provide a novel contactor assembly of the type briefly outlined above which is quick-releasing with respect to either pair of contacts so that the switching of circuits may take place rapidly, thus avoiding undue arcing at the contact points.

Another and important object is to provide such a contactor assembly for dual circuit control which requires but a small amount of low voltage current consumption for its operation. A similar and related object is to provide a dual circuit contactor which will operate to maintain one of the two circuits involved closed indefinitely with no current consumption whatsoever and to maintain the other circuit closed under the influence of a current of low voltage.

Yet another object of the invention is to provide a contactor assembly of this type in which a permanent magnet and an electromagnet may be employed without requiring a reversal of the current through the electromagnet, as is usual in the prior art, to make the permanent magnet effective.

The provision of a contactor assembly which is rugged and durable and which therefore is possessed of a comparatively long life; one which is comprised of a minimum number of moving parts and which therefore is unlikely to get out of order; one which is extremely compact so that it will occupy but small space; one which may readily be assembled and disassembled for purposes of inspection, replacement or repair; one which is comprised largely of metal stampings and which may therefore be manufactured at a low cost, and one which otherwise is well adapted to perform the services required of it, are further desirable features that have been borne in mind in the production and development of the present invention.

In the accompanying two sheets of drawings forming a part of this specification, a preferred embodiment of the invention has been shown.

In these drawings:

Fig. 1 is a top plan view of a contactor assembly constructed in accordance with the principles of the invention;

2

Fig. 2 is a sectional view taken substantially along the line 2—2 of Fig. 1;

Fig. 3 is a sectional view taken substantially along the line 3—3 of Fig. 1;

5 Fig. 4 is a side elevational view of the structure shown in Fig. 1; and

Fig. 5 is a circuit diagram showing the contactor assembly operatively disposed in an exemplary work circuit.

Referring now to the drawings in detail, the contactor

10 assembly involves in its general organization a base plate 10 of a suitable electrical insulating material, the plate serving as a support for all of the operative contactor elements. As shown in Fig. 3, the base plate 10 has mounted thereon at its opposite ends first and second contact groups 11 and 12 which are preferably of identical construction. A magnetic yoke in the form of a flat plate 13 of magnetizable material such as soft iron is positioned in face-to-face contact with the base plate 10 and a plurality of clamping screws 14 pass through the yoke 13

20 and are threaded in a laterally turned flange 15 provided on an armature support 16. The armature supporting end of the support 16 is formed with a pair of spaced upstanding lugs 17. A magnetizable metallic armature 18 in the form of a rectangular plate is movably positioned to overlap both magnets so as to be within the magnetic influence thereof. The said armature is preferably supported medially of its ends on the upper edge of the support 16. The edges of the armature 18 are slotted as at 20 (Fig. 3), with the slots registering with 30 the lugs 17. Retaining pins 21 extend through the lugs 17 to retain the armature in position on the support 16 while permitting slight rocking movement of the armature thereon for purposes that will appear presently.

The opposite ends of the armature have supported 35 thereon first and second brush assemblies 22 and 23 respectively, including brush elements proper 50, 55 designed for cooperation with the respective contact groups 11 and 12.

A permanent magnet 25 is composed of extremely hard 40 metal, for example "Alnico." It is disposed between the armature support 16 and contact group 11 and is secured in position on the magnetic yoke 13 by a screw 26 passing through the latter and threaded into a plug or core 27 embedded in the body of the magnet 25. The core 27

45 is composed of softer metal to facilitate the use of the usual equipment for forming the internal threads. An electromagnet 30 having a core 31 and a winding 32 is disposed between the armature support 16 and the contact group 12 and is secured in position on the yoke 16 50 by a screw 33 passing through the yoke and threaded into the core 31. The upper faces of the permanent magnet 25 and core 31 are substantially flat and horizontal and, as a consequence, the armature 18 is of obtuse V-shaped in longitudinal cross section in order that, upon 55 rocking movements thereof, the underneath face of the armature may move into face-to-face magnetic engagement with these two surfaces alternately during operation of the contactor assembly.

The contact groups 11 and 12 being of similar construction, it is thought that a description of one will suffice for the other. The contact group 11 is best illustrated in Fig. 2 and comprises a pair of contact elements 34 and 35, the latter element being in the form of an L-shaped stamping, preferably of copper which is

65 supported on an L-shaped bracket 36 and held in position by a clamping screw 37. A copper connector strap or bus bar 38 has one end thereof clamped between the support 36 and contact 35 and extends longitudinally of the assembly to a corresponding arrangement of parts 70 including a contact element 40 associated with the contact group 12. A terminal screw and washer assembly

39 are carried medially on the connector strap 38 for connection to a lead-in wire 42. The support 36 is secured on the base 10 by a clamping screw 43.

The contact 34 is generally U-shape and has an in-turned foot which is supported on a separator strip 45, a clamping screw 46 serving to hold the various parts in position. The contact 34 carries a terminal screw 47 to which a lead-out wire 48 may be attached.

The brush assembly 22 which is carried at one end of the armature 18 includes a brush proper 50 preferably formed of copper and operable in the manner of a bridging contact to bridge the two contacts 34 and 35 and complete the otherwise open current path extending from the lead 42 to the lead 48. The brush 50 is slidably carried on a post 51 which is secured by a screw 52 to an ear 53 formed on the end of the armature 18. A head 54 and seating washer 55 limit the downward movement of the brush 50. A spring 56 surrounds the post 51 and normally urges the brush to an advanced position on the post. A guide plate 51a is secured to the armature and slidably engages the brush bar to hold the same from rotational movement about said post 51. As will be explained later, the armature 18 is adapted to be attracted by the permanent magnet 25 so that it will assume the position shown in Fig. 3 wherein the brush 50 engages and bridges the contacts 34 and 35 and, when in this position, the head and seating washer 54, 54a become extended so that the spring 56 may force the brush 50 into positive engagement with the contacts 34 and 35.

The contact group 12, in addition to the contact element 40, includes a second contact element 41, the two contacts being mounted in assemblies similar to those shown in connection with the contacts 34 and 35 and similarly designated in the drawings. Likewise, the brush assembly 23 includes a brush element proper 55 mounted in the assembly 23 in the same manner that the brush 50 is mounted in the assembly 22. The spring 57 of the brush assembly has a slightly greater resistance to compressional forces than has the spring 56 for a purpose that will become clear presently.

As shown in Fig. 1, a lead-in binding post 58 and a lead-out binding post 59 are mounted on the base 10 on opposite sides of the electromagnet 30 and are electrically connected to the magnet winding 32 by wires 60 and 61 respectively. The post 58 is adapted to be connected through a preferably, but not necessarily manually operable switch S_w to the positive side of a suitable source of low voltage current as exemplified by the battery B (Figs. 1 and 5). The terminal 59 is adapted to be connected to the negative side of the battery B or ground.

The contactor assembly is shown in its normal position in Fig. 3 wherein the underneath face of the armature 18 is attracted to the north pole of the permanent magnet 25 and makes contact with the latter so that the spring 56 is under compression. With the parts in the position shown, the brush 50 bridges the contacts 34 and 35 while the brush 55 is raised from the contacts 40 and 41. In the exemplary circuit diagram shown in Fig. 5, a work circuit will thus exist from the source S, through lead 70, terminal 41, strap 38, contact 35, brush 50, contact 34, terminal 47, lead 48, load W1 which may be one of the field coils of a reversible electric motor, diagrammatically shown as a rectangle M in dotted lines, and lead 71 to the negative line.

The other field winding W2 of the motor M is disposed in a circuit parallel to the circuit just described and, when it is desired to close this latter circuit and open the former circuit, the switch S_w is closed manually to establish a circuit from the positive side of the battery B through lead 72, binding post 58 (Fig. 1), lead 60, winding 32 of the electromagnet 30, lead 61, binding post 59, and leads 73 and 74 to the negative side of the battery. Energization of the electromagnet 30

will attract the armature 18 to the south pole of the magnet core 30 to rock the armature 18 in a clockwise direction as shown in Fig. 3 and cause the brush 55 to bridge the contacts 40 and 41 and establish a circuit through the winding W2 and lead 75 to the negative line. Immediately prior to bridging of the contacts 40 and 41 by the brush 55, the brush 50 will be elevated from the contacts 34 and 35 to open the circuit through the winding W1.

It is to be particularly noted that with the electromagnet 30 deenergized the attraction of the permanent magnet 25, which is preferably formed of a nickel-iron-aluminum alloy known as "Alnico #5" and which has a high degree of residual magnetism, is sufficient to maintain the armature 18 attracted against the yielding action of the spring 56 as shown in Fig. 3. Upon energization of the electromagnet 30, a magnetic field is set up in and around the magnet structure resulting in a flow of magnetic flux which follows generally the path indicated by the full line arrows through the yoke 13, armature support 16, a portion of the armature 18 itself, and the core 31, as well as across the air gap 76 (Fig. 3) existing immediately prior to bridging of the contacts 40 and 41. This flow of flux opposes the residual magnetism of the permanent magnet 25 and "bucks" the normal flux flow set up by this latter magnet as shown by the dotted arrows on Fig. 3 so that the effective attractive force of the magnet 25 is materially weakened and the armature 18 is released thereby.

It is also to be noted from an inspection of Fig. 3 that with the magnet 30 deenergized and with the armature 18 elevated above the level of the upper surface of the magnet core 31, the magnet 30 has no effect upon the armature. Since the armature is in intimate contact with the north pole of the permanent magnet 25, a substantial portion, if not all, of the armature 18 is magnetized with the strength of the magnetic field decreasing in proportion to the distance of each increment of the iron material from the pole of the magnet 25. Thus when the magnet 30 becomes energized in such a manner as to render the upper end of the core 31 opposite in polarity to the thus magnetized armature, a very strong magnetic attraction exists between the armature 18 which at the time of its attraction to the magnet 30 has a polarity opposed to the polarity of the adjacent end of the core 31. The phenomena just described is conducive toward a powerful pull on the armature by the magnet 30 and a consequent rapid shifting of the various contacts. The pull of the magnet 30 is also assisted by the recoil of spring 56 which is somewhat stronger than the spring 57 and gives an initial impetus to the armature tending to cause it to rock in a clockwise direction with sufficient momentum that the spring 57 will become compressed to a sufficient degree to permit the armature to come within the sphere of magnetic influence of the electromagnet 30. Consequently, the armature 18 may be moved out of the range of influence of the permanent magnet by a minimum exertion of the electromagnet.

When it is desired to restore the original circuit through contacts 34, 35 to open the contacts 40, 41, it is merely necessary to open the switch S_w to deenergize the electromagnet 30. The spring 57, having been under compression, will recoil to give an impetus to the armature 18 to rock it in a counter-clockwise direction sufficiently to bring it into the range of the magnetic influence of the permanent magnet 25.

The invention is not to be limited to the exact arrangement of parts shown in the accompanying drawings or described in this specification except insofar as such limitations appear in the claims. It will be obvious that various changes in the details of construction may be resorted to without departing from the spirit of the invention. It will be also understood that the size of the unit and the character of the loads W1 and W2, which are not necessarily the field windings of a reversible motor

as described, will determine the selection of high and low operating voltages for the work and control circuits respectively.

We claim:

1. An electrical contactor assembly comprising in combination, a pair of spaced contacts, a permanent magnet having a relatively high degree of residual magnetism, an electromagnet having a fixed core separate from said permanent magnet and in opposite polarity thereto whose polarity is reversed with respect to the polarity of the permanent magnet; means defining a magnetic yoke common to both magnets including a base plate engaging said permanent magnet and said core, a magnetizable armature positioned to overlap both magnets and having one end engageable with the permanent magnet and its other end engageable with the electromagnet; said armature when in one extreme position being disposed within the magnetic field of the permanent magnet and operative to establish an electrical circuit through said contacts, and an armature support connecting said base and the armature medially of the latter and serving as a common path for the magnetic flux of both magnets, whereby the energization of the electromagnet sets up magnetic flux in said common yoke in opposition to the residual magnetism of said permanent magnet and effects release of said armature for movement thereof out of the magnetic field of said permanent magnet.

2. An electrical contactor assembly as defined in claim 1 characterized in that said armature support is fixed and is comprised of magnetic material and is in direct contact with said magnetic yoke at one end and is pivoted to said armature medially of the latter at its other end, whereby when the latter is attracted to the permanent magnet a closed flux path exists through the yoke, permanent magnet, armature and support, and whereby when the armature is attracted to the electromagnet a closed flux path exists through the yoke, armature support, armature and electromagnet core.

3. An electrical contactor assembly comprising in combination, a magnetic yoke, an armature support formed of magnetic material extending medially from said yoke, a permanent magnet having its body extending from said yoke on one side of the support, an electromagnet having a core separate from said permanent magnet and in opposite polarity thereto extending from said yoke on the other side of said support, an armature common to said permanent magnet and electromagnet pivoted medially of its ends to said armature support for limited rocking movement between one extreme position wherein one end thereof is disposed within the magnetic field of the permanent magnet and another extreme position wherein the other end thereof is disposed within the magnetic field of the electromagnet when the latter is energized, electrical contact structure at one end of said armature and movable with the latter, said yoke, armature support, armature and core constituting a closed flux path for the electromagnet when the latter is energized, said yoke, armature support, armature and magnet body constituting a closed flux path for the permanent magnet when the armature is attracted thereto, and means for supplying a predetermined current flow to said electromagnet in a direction to set up a flow of flux in said closed path of the electromagnet in opposition to the flow of flux in said closed path of the permanent magnet.

4. An electrical contactor assembly comprising, in combination, a magnetic yoke, an armature support formed of magnetic material extending medially of said yoke, a permanent magnet having its body extending from said yoke on one side of said support, an electromagnet having a core extending from said yoke on the other side of said support, an armature common to said permanent magnet and electromagnet pivoted medially of its ends to said armature support for limited rocking movement between one extreme position wherein one end thereof is disposed within the magnetic field of the permanent mag-

net and another extreme wherein the other end thereof is disposed within the magnetic field of the electromagnet when the latter is energized, electrical contact structure at one end of said armature and movable with the latter, said yoke, armature support, armature and core constituting a closed flux path for the electromagnet when the latter is energized, said yoke, armature support, armature and magnet body constituting a closed flux path for the permanent magnet when the armature is attracted thereto, means for applying a predetermined current flow to said electromagnet in a direction to set up a flow of flux in said closed path of the electromagnet in opposition to the flow of flux in said closed path of the permanent magnet, spring means operable when said armature is in

10 said one extreme position to bias the armature away from said extreme position, and spring means likewise operable when the armature is in its other extreme position to bias the armature away from said latter extreme position, said first mentioned spring means normally exerting a biasing effect on said armature less than the attractive force of said permanent magnet and said second spring means normally exerting a biasing effect on said armature less than the attractive force of said electromagnet when said predetermined flow of current is supplied thereto.

20 5. In a contactor assembly, a first pair of fixed spaced contacts, a second pair of fixed spaced contacts remote from said first pair of contacts, an armature support formed of magnetic material disposed between said pairs of contacts, an armature pivoted to said support medially

30 of its ends for limited rocking movement thereon, first and second brush members mounted on said armature at the opposite ends thereof respectively, said armature being movable between one extreme position wherein said first brush member electrically bridges said first pair of contacts and another extreme position wherein said second brush member electrically bridges said second pair of contacts, a permanent magnet positioned between said support and the first pair of contacts and operable upon one end of the armature, an electromagnet positioned between the support and the second pair of contacts and likewise operable upon the other end of the armature, a magnetic yoke bridging the core of the electromagnet, the support, and the body of the permanent magnet and positioned so that when a predetermined flow of unidirectional current is passed through the electromagnet, flux is set up in said yoke in opposition to the residual magnetism of the permanent magnet, a connector strap connecting one contact of the first pair of contacts with one contact of the second pair of contacts, and plural spring means operable when said armature is in either of its extreme positions for biasing the same away from said position.

40 6. In a contactor assembly, the combination set forth in claim 5 wherein the spring means which is operable to bias the armature from the extreme position it assumes when attracted by said electromagnet is of greater force than the other spring means.
